UNITED STATES PATENT OFFICE.

FRED W. KENNEDY, OF SHELBYVILLE, INDIANA, ASSIGNOR TO THE KENNEDY CAR LINER AND BAG COMPANY, OF SHELBYVILLE, INDIANA, A CORPORATION OF INDIANA.

LINER FOR BOX CARS.

Application filed July 14, 1923. Serial No. 651,573.

To all whom it may concern:

Be it known that I, FRED W. KENNEDY, citizen of the United States, residing at Shelbyville, in the county of Shelby and State of Indiana, have invented certain new and useful Improvements in Liners for Box Cars; and I do hereby declare the following to be a full, clear, and exact description of the invention, such as will enable others skilled in the art to which it appertains to make and use the same.

It is a well known fact that box cars and the like used for the shipment of small grains and other commodities, are not entirely satisfactory for such purposes for the reason that the grain frequently trickles out through cracks in the floor and other cracks or openings which frequently develop due to the rough handling to which the box cars are subject.

This invention relates to means for lining box cars, and has for its object to provide a liner that is particularly adapted for use in the corners of the car. The improved liner is made from strong paper and is so constructed and reinforced at its angles and bends that if the main body of the liner should burst at such places, the liner will nevertheless be effective for its intended purpose by reason of the improved reinforcements.

The various features of novelty and invention will appear from the detailed description taken in connection with the accompanying drawing forming part of this specification.

Referring to the drawings, Fig. 1 is a perspective view of the interior of one end of a box car, showing the corner liners in position therein;

Fig. 2 is a perspective view on an enlarged scale of the improved liner;

Fig. 3 is a section taken on line 3-3 of Fig. 2;

Fig. 4 is a section taken on line 4-4 of Fig. 2;

Fig. 5 is a section taken on line 5-5 of Fig. 2;

Fig. 6 is a section taken on line 6-6 of Fig. 2;

Fig. 7 shows the condition of the blank before the same is folded into the position shown in Fig. 2;

Fig. 8 is a fragmentary section on line 8-8 of Fig. 7;

Fig. 9 is a fragmentary section on line 9-9 of Fig. 7 and

Fig. 10 is a view showing one of the final steps in the folding up of the liner into its permanent form.

In the drawings, numeral 1 indicates a conventional box car and numeral 2 the improved liners which are placed in each corner of the car, and which cover the floor and sides of the car. While Fig. 1 shows only the corners at one end of the box car as being lined, it will be understood that the entire bottom and sides of the same will be lined. In this connection, attention is called to my prior Patent No. 818,257, patented April 17, 1906, over which the present invention is an improvement.

For convenience of description, the three main sides of the corner liner are indicated by the letters A, B and C,—A indicating the bottom of the liner, B one upright side of the same and C the upright side which is disposed against the end of the car.

In constructing the improved liner, two sheets of paper of substantially the same area are overlapped and glued together along one of their edges. The two sheets of paper which are thus united are indicated by numerals 3 and 4 respectively and the lapped over portions are indicated by reference characters 3' and 4'.

The overlapped portion is then given a bellows-like fold as indicated at 5 (see Fig. 3) which will allow relative displacement between the sheets 3 and 4, or sides A and B, without rupturing same. The fold 5 will normally be disposed lengthwise of the car, as will more readily appear herein-after.

After the lapped over portions have been folded to produce the bellows-like fold 5, and while the sides A and B are laid out flat as in Fig. 7, a looped reinforcement D is disposed across the sections 3 and 4 at right angles to the fold 5, and is cemented to the said sections 3 and 4. The said reinforcement D is looped intermediate its longitudinally extending edges, as at 6, as will more clearly appear by reference to Figs. 4, 5 and 6. At this point, it may be stated that the practice of providing the loop 6 in the reinforcement D is to provide an extensible safety section, which will serve to prevent separation of the adjacent sections of the paper if the same should burst along the

bottom corner line 7 and also along the upper corner line 8, as viewed in Figs. 2, 5 and 6. For convenience of description, the looped reinforcement between the sides B and C, which correspond to the reinforcement D between the sides A and C is designated by the reference character D'.

After the reinforcement D has been disposed across and pasted to the sections A and B, the said sections are slit as at 10 from the median line of the said reinforcement D toward one end of the said sections. The purpose of slitting the sections is to enable the same to be folded into position. Reference is made to Figs. 7 and 8, the next step may conveniently be the bending up of the section B at right angles to the section A, as shown in Fig. 8. The section B' may then be bent at right angles to the main section 20 B along the loop 6 of the reinforcement D and the section A' then bent up as indicated in Fig. 10, and the two sections A' and B' pasted together, whereupon the liner is complete.

By reference to Figs. 4 and 10, it will be seen that one side of the reinforcement D is disposed between the two walls A' and B'. By reference to Fig. 4, it will be seen that there are four thicknesses of material at 30 the lower edge of the main wall C. The outer ply of material is the main section A', the next is one of the side flaps of the reinforcement D, the third is the section B' and the fourth is part of the overlapping 3', which adheres to the section B' after the slit 10 has severed the sections A' and B',—this overlapping being conveniently designated 3a.

After the liner has been given its final shape, some of the material which constitutes the bottom loop 5 will extend up along the outside of the liner in the form of surplus material 5'. This material serves no useful purpose and if desired can be removed from the finished liner, but its presence does no harm and simplifies the manufacturing operation inasmuch as it is merely necessary to slit the sections as at 10 and then to fold the liner into shape, as will be 45 readily understood.

It will now also be understood that the reinforcement D constitutes a reinforcement not only along the bottom corner line of the liner but also along the upright corner line 55 of the same. It therefore follows that if the main sheet should burst at the upright corner line 8, that no material damage would result to the liner and that the same would remain effective because the loop 6 of the reinforcement D' would close the breach and prevent any leakage of grain or of material through the crevice or rupture.

It will be understood that the entire floor and sides of the box car will be lined with 65 paper. The bottom and sides of the corner

liners may be made as long as may be necessary or practical from a manufacturing standpoint. In any event, the entire car will be lined as said. It will also be understood that the reinforcement between the sides, 70 that is to say at the angle or bend can be incorporated into the liners for lining the bottom and sides of the car as distinguished from the corners.

What I claim is:

1. A car liner for the corners of box cars comprising two upright sides disposed at right angles to each other and a bottom member joined to the bottom edges of the upright sides, the joint between the bottom and one of the sides including a loop member affixed to the bottom and said side, the loop being disposed opposite the line of joinder between said bottom and side. 75

2. A car liner for the corners of box cars comprising two upright sides disposed at right angles to each other and a bottom member joined to the bottom edges of the upright sides, the joint between the bottom and one of the sides including a loop member affixed to the bottom and said side, the loop being disposed opposite the line of joinder between said bottom and side, and the joint between the side walls including a looped member. 80

3. A corner liner for box cars comprising two sheets of paper lapped over and cemented along one of their edges, the lapped-over portion being folded back to constitute a bellows-like fold, a reinforcement member disposed transversely across the sheets and cemented thereto, said member having a loop intermediate its longitudinal edges which projects free away from the paper, the said over-lapped portion being slit lengthwise of the same from a point starting at the reinforcement member, said slit serving to divide the two sheets into sections which jointly constitute one wall of the liner. 100

4. A blank for making car liners comprising two sheets of paper over-lapped and cemented along one of the longitudinal edges, the over-lapped portion being looped back to form a bellows-like portion, a looped reinforcing member extending transversely across the over-lapped portion and extending toward the said two sheets, the said sheets being slit lengthwise thereof from said reinforcing members. 105

5. The method of making a corner liner from two main sheets of paper comprising over-lapping and cementing two longitudinally extending edges of paper, placing a looped reinforcing member across the paper and cementing it thereto, slitting the over-lapped portions longitudinally from a point beginning at the said reinforcing member, bending the sheets along the bellows-like fold, and bending the sections formed by slitting along the lines lying within the said 120

125

130

reinforcing member and finally cementing the said sections together.

6. A liner for the floor and sides of box cars comprising a member adapted to be bent intermediate its edges, and a reinforcement at the bend consisting of a looped-over portion, said looped over portion permitting relative displacement between the angularly disposed sides without rupturing at the line of

10 bend.

7. A liner for the floor and sides of box cars comprising two sheets of paper overlapped for a portion of their area, said overlapped portion having a section which is reversely bent to form a bellows-like loop, and said loop permitting the body of the paper on either side of the loop to partake of relative displacement without rupture.

15 In testimony whereof I affix my signature.

FRED W. KENNEDY.
